HERMAN COHN, OF NEW YORK, N. Y.

PROCESS FOR MANUFACTURING HATS.

1,243,487.

Specification of Letters Patent. Patented Oct. 16, 1917.

Application filed June 25, 1917. Serial No. 176,806.

To all whom it may concern:

Be it known that I, HERMAN COHN, a citizen of the United States, residing at New York, in the county of New York and State 5 of New York, have invented certain new and useful Improvements in Processes for Manufacturing Hats, of which the following is a specification.

My invention relates to methods for pressing and cutting out hats made of fabric, such as velvet or the like, in which it is customary to first press and shape the brim of the hat from a suitable blank or piece of material and then cut out a space in the 10 center of the hat for attaching the crown thereof, which is made of a separate piece of material. It is customary to leave a flange of about an inch in height around the central opening of the piece of material, so 15 as to enable the brim of the hat to be fastened. This flange enables the sewing on of the crown of the hat.

It has heretofore been customary in pressing and shaping the brim of the hat, to provide two pressing dies, one above the other, which were suitably heated so as to facilitate the pressing of the material. These dies had their adjacent surfaces of the 20 shape of the brim of the hat and the lower die had at or near its center, a depression of about an inch in height, this depression corresponding to the shape of the opening for receiving the crown of the hat. Instead 25 of providing a depression in the lower die, it could also be cut away at this point so as to leave an opening in its surface corresponding to the opening for receiving the crown of the hat. The upper die had, at 30 its bottom, a projection corresponding in shape to the depression or opening in the lower die.

In the operation of this device, two workmen would take an unperforated piece of material of sufficient area to provide for the 35 brim of the hat and they would hold it at the top of the lower die. Then the upper die would be caused to descend upon the material held on the lower die, by any suitable means, such as a foot press or the like. The upper die would press the material on 40 the lower die, thus shaping it, and it would also force the material above the depression or opening in the lower die, into this depression or opening. When the upper die 45 was removed, the line where the material had been forced into the depression or open-

ing in the lower die, could be seen by the operator, because the heating and pressing left a mark at that point.

After this was done, the operator would 50 cut away the center of the pressed piece of material, leaving a flange of about an inch to receive the crown of the hat which was then sewed on.

This method has led to a waste of material in that the upper die would always force the fabric into the opening or depression in the lower die, so that instead of using a piece of material of the exact size of the brim of the hat, it was always necessary to allow for at least an inch more 60 all around the brim of the hat. This has been a considerable item of loss in working with expensive velvets, especially since hundreds of hats are usually made by a single manufacturer. In addition, the operation of this device was not always reliable 65 because the men who were feeding the material to the dies had to hold it against the pull that was exerted by the upper die forcing the material into the opening of the 70 lower die.

The object of my invention is to provide a new and improved method of pressing and shaping the brim of the hat, that shall be 75 uniform and reliable, economical of material, and shape and press the hat more effectively.

I will describe one of the machines that may be used for practising my new and improved method, in the following description and drawings in which Figure 1 is a front elevation of the dies used for practising my 80 new and improved method.

Fig. 2 is a view showing two of the dies 85 of Fig. 1 pressed together for the first operation.

Fig. 3 is a view of the dies pressed together for the third operation.

These figures illustrate the structure 100 shown in my companion application Serial No. 176,807 of even date, illustrating a complete machine for carrying out this method, and entitled "Machines for pressing and forming hats".

To carry out my new methods, the operators take an unperforated piece of fabric of suitable size for forming the brim of the hat and place it between the lower annular die 14 and the upper annular die 15.

The opening of these dies is of a shape 110 corresponding to the opening that must be

cut in the blank, for sewing on the crown of the hat to the brim. These dies 14 and 15 have their adjacent surfaces inclined to the vertical so that their shape, generally speaking is frusto-conical. Their adjacent surfaces have substantially the same contour, there being just enough difference of taper between them to tightly draw and uniformly stretch a piece of fabric that is pressed between them.

Above the opening in the annular upper die 15, is a supplemental die 22, which is adjusted to fit into the opening of the upper annular die 15. This uppermost supplemental die 22 carries on its underside four blades 23, which are arranged at right angles to each other and radiate from the center of the die 22. These blades or knives 23 have a tapering shape as is clear from Figs. 1 and 2, the widest portion of these knives being at their outer ends. These knives 23 do not extend to the edge of the die 22 as can be seen from the drawings.

After the piece of unperforated material is held against the top of the lower die 14, the upper die 15 is then caused to descend by any suitable means and it clamps the piece of cloth, such as velvet or the like, against the lower die 14. By reason of the slight difference in contour of the adjacent surfaces of the dies 14 and 15 which has been before mentioned, the fabric is tightly and uniformly stretched in all directions from the center of the die 14, so that its surface is not wrinkled and is tightly extended over the central opening in the die 14. Of course, this stretching is not made so great as to injure the fabric, and if desired, the adjacent surfaces of the dies could be given the identical contour.

The dies are heated by any well-known heating means and by reason of the combined heat, pressure and tension, the ironing and shaping of the hat is accomplished in a superior manner, without any wrinkles or the like, even if the operators have not fed the material carefully between the dies 14 and 15.

This operation does not cause any pressing of that portion of the blank not intended for the brim.

While the material is thus uniformly stretched over the die 14 and is tightly clamped by the die 15, the supplemental die 22 is caused to descend. The outmost points of the blades 23, penetrate the fabric at a suitable distance from the opening in the upper die 15 and then gradually cut the fabric inwardly toward the center until four slits at right angles to each other have been cut in that portion of the fabric which has been stretched over the opening of the die 14.

Then the supplemental die 22 enters the opening in the lower die 14, and forms a

flange of any desired height, to which the crown of the hat is to be sewed. By reason of the heat, this flange is marked upon the fabric so that it is visible to the workers.

When the blank has thus been cut and shaped, the die 22 and then the die 15, are withdrawn from the die 14 and the operator cuts off the superfluous portions of the four tongues which have been formed by the cutting of the four slits in the fabric by the four blades 23, leaving a flange to which the crown of the hat can be sewed.

By this new and improved method, the workings of the dies are visible to the operators at all times, the flange is not formed until the fabric has been tightly stretched and clamped in a uniform manner in all directions, the forming of the brim is accomplished under tension, and marked economy of material and superiority of operation are secured.

While I have described one mechanism for carrying out my method, it is clear that numerous other mechanisms might be devised therefor, that the various parts might be made to move automatically, and that my invention is not to be limited to the details before set forth, either of mechanism or manipulation, but that numerous changes and modifications could be made without departing from the spirit of my invention, as defined in the following claims.

What I claim is:—

1. A method of forming hats which consists in stretching an unperforated blank of material, heating and pressing that portion of said blank intended for the brim of the hat, perforating the central unpressed portion of said blank while it is maintained in its stretched condition, and then releasing said blank from the aforesaid stretching, heat, and pressure.

2. A method of forming hats which consists in heating and pressing that portion of said blank intended for the brim of the hat, to the shape of said brim, without exerting any pressure against the central portion of said blank which is not intended for said brim, and perforating the central unpressed portion of said blank after the said pressing and heating have been performed.

3. A method of forming hats which consists in stretching an unperforated blank of material, heating and pressing that portion of said blank intended for the brim of the hat, perforating the central unpressed portion of said blank while it is maintained in its stretched condition, then releasing said blank from the aforesaid heat and pressure and forming the flange portion for the crown of said hat from the part of the blank so cut.

4. In the art of making and pressing hats those steps in the art which consist in stretching a blank of material having the

same area as the brim portion of said hat plus that of the central opening in said brim intended for the insertion of the crown of the hat, pressing only that portion of said blank intended for said brim portion into the desired shape while said blank is maintained in a stretched condition, and perforating the unpressed portion of said blank.

5. A method of forming hats which consists in stretching an unperforated blank of material, clamping that portion of said blank

intended for the brim of the hat, and cutting the unclamped portion of said blank to enable the formation of a flange for receiving the crown of said hat, said un- 15 clamped portion of said blank being first perforated adjacent the clamped portion thereof.

In testimony whereof I hereunto affix my signature.

HERMAN COHN.
